VEHICLE DOOR SUPPORT

Rudolph I. Schonitzer, Auburn, Ind.

Application July 25, 1932, Serial No. 624,411

10 Claims. (Cl. 296—44)

This invention relates to improvements in vehicle door supports adapted to prevent relative play between the door and its frame and rattling thereof when the door is closed, and pertains to 5 that class of inventions set forth in my previous application for Door supports, Ser. No. 606,941, filed April 22, 1932.

One of the objects of this invention is to incorporate in a structure having a door frame and 10 a door hinged therein automatically operable means whereby the door when closed in its frame is held therein so that vibratory relative movement of the door when closed and its frame, more particularly in directions parallel with the plane 15 of the door, is substantially obviated.

Usually, to facilitate operations in the manufacture of vehicle bodies the doors are so proportioned relative to the frames as to permit the doors to be fitted in their frames readily without binding which ordinarily allows play of the door in its frame with resultant vibratory action therebetween when the vehicle is in motion.

A further object of the invention is to provide supports operably associated with the door and its 25 frame by means of which the door when closed is firmly sustained in its frame independently of its hinges and lock whereby movement of the door in the plane of the frame is circumvented.

Other objects and advantages of the invention 30 will appear in the following description.

The invention as herein illustrated and described with reference to certain physical embodiments is of a preferred form and is susceptible of modification and may be embodied in various 35 other forms within the scope of my claims without departure from the spirit of the invention.

An illustrative embodiment of the invention in a preferred form is shown in the accompanying drawings, in which:—

40 Fig. 1 is a side elevation of a vehicle body equipped with the invention, parts being broken away;

Fig. 2 is a detail horizontal section of Fig. 1 on the line 2—2 thereof;

45 Fig. 3 is a similar detail horizontal section of Fig. 1 on the line 3—3 thereof; and

Fig. 4 is a section projected from Fig. 2 in a plane at right angles thereto.

In the illustrative embodiment of the invention 50 is shown a vehicle body 1 provided with a sill 2, roof-rail 3, hinge pillar 4 and lock-pillar 5 arranged to form a door frame in the usual manner. In the opening of the frame is disposed a door 6 that is supported upon hinges 7 which connect 55 the hinge-rail 8 of the door with the hinge-pillar

4 of the frame. The lock pillar has thereon buffers 9 against which the lock-rail 10 of the door bears when closed, and a lock 11 is provided for securing the swing side of the door in connection with the lock-pillar in the usual manner. 5 The door is so proportioned relative to the frame as to provide a clearance space 12 between the door and the adjacent sill, roof-rail, hinge-pillar and lock-pillar of the frame, to permit tolerable variations of the clearance space and alinement of 10 the door within the door opening in the frame such as ordinarily occur in manufacture and during use of the vehicle.

The hinge-pillar 4 of the frame has contact members or stops 13 secured in connection therewith located preferably adjacent the top and bottom of the door opening, and which project from the butt face 14 of the hinge-pillar 4 into the clearance space 12 so that when the door is closed 15 the butt face 15 thereof bears with force against 20 said stops.

In the lock-pillar 5 of the frame and exposed upon the butt face 16 thereof is secured a hollow guide block 17 the front of which is open and in which is disposed a take-up member 18 that 25 has horizontal movement therein transverse to the lock-pillar. Preferably, the upper and lower edges of the take-up member 18 and the corresponding inner faces 20 of the block 17 extend divergently whereby the take-up member is held 30 in operative position in the block. Rods 21 disposed lengthwise in the block 17 extend loosely through the take-up member, and compression springs 22 disposed concentrically upon the respective rods extend from the inner end 23 of 35 the block into corresponding counterbores 24 in the take-up member and urge said member toward its outermost end position. The outer face 25 of the take-up member 18 slants outwardly toward its inner end and projects into 40 the clearance space 12 between the lock-pillar 5 and the lock-rail 10 of the door.

Upon the butt face 26 of the lock-rail 10 of the door is rigidly secured a contact member 27 at a point thereon located so as to have engagement with the take-up member 18 when the door is closed. The outer face of the contact member 27 extends preferably in a plane parallel with the engaging face of the take-up member 18. The guide block with its spring-pressed take-up member and the contact member constitute a take-up support that co-operates with the stops 13 in sustaining the door when closed against movement toward and from the lock and hinge pillars, and compensates for the variations in the 55

clearance space between the frame pillars and the door.

Preferably, suitable spacers 28 are interposed between the guide block 17 and the lock-pillar 5, and between the contact member 27 and the lock-rail 10 of the door to bolster the take-up support and also to deaden sound incidental to concussions occasioned by closing the door.

As a further means to circumvent frictional 10 sounds and to provide lubrication for the movable take-up member 18, a recess 29 is made in the back thereof which is filled with a suitable oil-laden wick 30 by which lubricant is supplied to the contacting surfaces of the take-up member 15 and its block.

The clearance space 12 is closed to the interior of the vehicle body when the door is shut, by means of suitable trimmings 31 applied in the usual manner.

20 In operation, when the door is open the movable take-up member 18 is held in its outermost end position against the corresponding outer end 23' of its guide block 17, and as the door is swung to closed position in the door-frame the contact member 27 engages the take-up member which is thereupon accommodately moved in opposition to the pressure of the springs 22 until the door is secured against the buffers 9 by its lock 11. Concurrently with closing of the door, 30 the stops 13 are moved into bearing engagement with the butt-face 15 of the hinge-rail of the door so that when closed the door is held by the stops and the take-up support in a state of compression horizontally between the hinge and lock pillars of the frame, whereby vibratory movement or play of the door between said pillars is taken up. Thus, upon closing of the door its hinges are materially relieved of the strain due to the weight or vibratory action of the door 40 which insures silence and prolongs the life of the hinge connections and lock for the door as well as the door and its frame.

The present invention may be used in conjunction with that disclosed in my said previous 45 application by installing in connection with the roof-rail 3 and the top-rail 3' of the door a take-up support 32, and in connection with the sill 2 and bottom rail 2' a pair of opposing contact members 33 and 34 so as to suitably take 50 up vertical play of the door between the sill and roof-rail. In such instance when the door is closed it is wedged between the hinge and lock pillars and also between the sill and roof-rail so that relative movement between the door and frame vertically as well as fore and aft in their 55 common plane is completely obviated.

While there are shown but two stops 13 in the drawings operatively associated with the hinge-rail of the door and hinge pillar of the frame, 60 and but a single take-up support operatively associated with the lock-rail of the door and lock-pillar of the frame, if so desired the stops may be more numerous and distributed at suitable points on the hinge-pillar or the hinge-rail. 65 Also, the take-up support may be augmented by installing additional similar supports at suitable locations in connection with the lock-rail and lock-pillar and thus effect a more general distribution of the sustaining pressure applied to the door.

70 I claim:—

1. In means to support a hinged door when closed and in the door-frame of a vehicle and independently of the hinges thereof, stops operatively associated with the hinge-rail of the door

and the hinge-pillar of the frame, and a take-up support constituted of members mounted in connection with the lock-rail of the door and lock-pillar of the frame co-operatively associated with said stops to prevent fore and aft movement of 5 said door within said frame.

2. Means to support a hinged door when closed and in the door-frame of a vehicle and independently of the hinges thereof, consisting of stops so located as to form bearings between the 10 hinge-rail of the door and the hinge-pillar of the frame, and a take-up support operatively associated with the lock-rail of the door and the lock-pillar of the frame so arranged that when the door is shut opposing pressure is applied to the door between said stops and take-up member to prevent vibration of said door within said frame.

3. In means to support a hinged door when closed and in the door-frame of a vehicle and independently of the hinges thereof, stops operatively associated with the hinge-rail of the door and the hinge-pillar of the frame, and a support in connection with the lock-rail of the door and lock-pillar of the frame having a 25 spring-pressed take-up member and complementary contact member co-operatively associated with said stops adapted to take up fore and aft play of the door in said frame when the door is closed, and compensate for variations in the 30 clearance and alinement of the door respecting said frame.

4. In means to support a hinged door in the door frame of a vehicle, contact members operatively associated with the hinge-rail of the 35 door and the hinge-pillar of the frame and with the bottom of the door and sill of the frame, and take-up supports operatively associated with the lock-rail of the door and lock-pillar of the frame and with the top of the door and the 40 roof-rail of the frame, said contact members and take-up supports being so arranged that when the door is shut opposing pressure is applied to the door vertically and fore and aft between said contact members and corresponding 45 take-up supports.

5. In means to support a hinged door when closed and in the door frame of a vehicle and independently of the hinges thereof, a series of 50 contact members and take-up supports operatively associated with the door and frame of the vehicle arranged in connection therewith in opposite positions so that when shut the door is sustained within the frame between said contact members and take-up supports under vertical 55 and fore and aft pressure and independently of the door hinges.

6. In combination with a vehicle body provided with a door frame, a door hinged therein and a lock securing the door in closed position 60 in said frame, of means for supporting the door when closed independently of its hinges and comprising a series of stops and take-up supports arranged operatively in connection with the door and frame in relatively opposite positions, said supports having spring-pressed movable members and complementary contacting members co-operatively associated with said stops so arranged that when shut the door is sustained thereby under vertical and fore and aft pressure 70 in the frame between said stops and supports independently of the door hinges.

7. The combination with a vehicle body having a door frame, a door having clearance within the frame, and door hinges, of means to sup- 75

port the door when closed independently of its hinges comprising a stop located between the hinge edges of the door and frame, and pressure exerting means located between the lock edges of the door and frame for applying pressure to the door in one direction and to the frame in the opposite direction to bind the door between said pressure exerting means and said stop to prevent movement of the door within and independently of the frame.

8. The combination with a vehicle body having a door frame, a door having clearance within the frame, and door hinges, of means to support the door when closed independently of its hinges comprising a stop located between the hinge edges of the door and frame, and pressure exerting means located between the lock edges of the door and frame for automatically applying pressure to the door in one direction and to the frame in the opposite direction upon closing the door to bind the door between said pressure exerting means and said stop to prevent movement of the door within and independently of the frame.

9. The combination with a vehicle body having a door frame, a door having clearance within the frame, and door hinges, of means to support the door when closed independently of its hinges comprising a rigid door stop carried by the hinge

pillar of the door frame for engagement by the hinge edge of the door when the latter is closed, and pressure exerting wedge means located between the lock edges of the door and frame for automatically applying pressure to the door in one direction and to the frame in the opposite direction upon closing the door to bind the door between said pressure exerting means and said stop to prevent movement of the door within and independently of the frame.

10. The combination with a vehicle body having a door frame, a door having clearance within the frame, and door hinges, of a stop located between the hinge edges of the door and frame, pressure exerting means located between the lock edges of the door and frame for applying pressure to the door in one direction and to the frame in the opposite direction to bind the door between said pressure exerting means and said stop, and other pressure exerting means located between the top rail of the door and the top rail of the frame and also between the bottom rail of the door and the bottom rail of the frame, said pressure exerting means applying pressure to the door in one direction and to the frame in the opposite direction.

RUDOLPH I. SCHONITZER.
